FLUID MOVING MEANS

Thomas E. Quick, Wichita, Kans.

Application March 5, 1954, Serial No. 414,357

7 Claims. (Cl. 230—117)

This invention relates to the movement of fluids. In a more specific aspect, this invention relates to new means for moving fluids, particularly air. In a still more specific aspect, this invention relates to a new type of fan having centrifugal fan means longitudinally disposed within a housing which cooperates with same to result in highly efficient air movement. In still another specific aspect, this invention relates to new means for moving fluids, particularly air, from one point in a system to another through a conduit, such as must be done in a forced draft heating system or in supplying fresh atmospheric air to an inner point or area in a building.

This application is a continuation-in-part of my pending application Serial No. 375,894.

Fans having radially disposed blades and squirrel cage blowers transversely disposed in a conduit have long been known in the art of fluid movement, they being used primarily to exhaust and set air in movement or to transfer air through a conduit, respectively. Both such radially bladed fan and the squirrel cage blower have their disadvantages in that they require a substantial amount of space for installation, normally much more room than is provided in the usual conduit through which the fluid such as air moves. In addition, a radially bladed fan is a cumbersome type of air moving means which cannot be used in all desirable locations.

I have invented fluid moving means. The new means of my invention has a body, one end portion of which is conoidal and rotatable and the other end portion of which is fixed and which has a smooth and gently curved surface. In one preferred embodiment of the new fluid moving means of my invention the fixed portion of the body is streamlined, while in another it is mushroomed to smoothly direct fluid outwardly. The conoidal end portion of the new means of my invention has a plurality of centrifugal blower blades mounted around the base thereof parallel to the longitudinal axis of the body. In my device there is a housing mounted around the rotatable end portion of the body and a portion of the fixed portion of the body, such housing having an inlet for fluid forward of the rotatable end portion and an outlet for fluid to the rear of the rotatable end portion. The rotatable end portion of my device having the centrifugal blower blades and the housing preferably define a fluid flow area smaller at the rear end portion than at the forward end portion of the rotatable end of the body, and it is preferred that the change in fluid flow area be substantial from the intake to the rear of the rotatable end of the body. The housing of my device is preferably substantially cylindrical, the rotatable end portion of the body and the housing forming a path of gradually decreasing cross sectional flow area through which the fluid moved by the device of my invention is accelerated. The end of the body of the device of my invention having the centrifugal blower blades is rotated by actuating means desirably being mounted in the fixed end portion of the body. Fluid such as atmospheric air moves in through the inlet of the housing and is discharged through

2

the outlet formed by the housing and fixed portion of the body to the rear of the rotatable end portion. The velocity of this air preferably continually increases during passage from the housing inlet to a point near the rear of the rotatable end portion of the body of my new device, resulting in lowering the pressure within the housing to further increase the pressure differential between the inside and outside of the housing and increasing the flow of air through the use of the device of my invention. In a preferred specific embodiment of my invention, I provide fin means to straighten the flow of spiraling air from the rotatable end portion of the body of my device.

The new fluid moving device of my invention is very useful as a fan to circulate air, for example in a room, and because of its configuration it can conveniently be placed on bookcases, mantels, and the like, where the ordinary fan having radial blades of sufficient size will not sit so as to move the air parallel to the walls of the room. With the new air moving means of my invention of relatively small diameter, circulation of a great amount of air substantially parallel to the walls of the room can easily be obtained. In addition, as one skilled in the art can see the fluid moving means of my invention can be made much more attractive than the usual radially bladed fan.

In a desired specific embodiment of the new centrifugal blades moving means of my invention, I install the body of my device having the rotatable end with the centrifugal blower blades in a fluid conduit, for instance, the cold air return conduit of a forced air furnace. In this embodiment, the housing of my device forms a portion of the fluid conduit. The combination of the device of my invention and the conduit results in very economical and efficient circulation of air, which is necessary for the proper functioning of the heating system. The fluid moving apparatus of my invention can be installed in the usual air conduit without appreciably enlarging same, preferably forming with the housing portion of the conduit a cross sectional flow area of decreasing size from the front to the rear of the rotatable end of the body of my device to accelerate the air and create pressure differential in addition to that created by rotation of the end portion having the centrifugal blower blades. This results in quiet and efficient air circulation. The saving in installation cost over the usual fan having radially disposed blades or a transversely disposed squirrel cage blower is substantial.

It is an object of this invention to provide new means for moving fluid.

It is another object of this invention to provide new means for the movement of fluid within an enclosure or for the movement of fluid by conduit such as from a point outside to a point inside an enclosure.

It is a further object of this invention to provide new fan means which are efficient, economical and which require less space in which to operate than the usual fan means having radially disposed blades.

Still another object of this invention is to provide new fluid moving means wherein a rotatable end portion of a body having longitudinally disposed centrifugal blower blades cooperates with a housing for same to result in pressure differential which in turn results in moving fluid.

Yet another object of my invention is to provide co-operating conduit and longitudinally disposed centrifugal blower means which result in an efficient and economical means to move fluid in a system such as a forced draft heating system.

Other objects and advantages of the fluid moving means of my invention will become apparent to one skilled in the art upon reading this disclosure.

Drawings accompany and are a part of this disclosure. Such drawings depict preferred specific embodiments of the new fluid moving means of my invention, and it is to be understood that such drawings are not to unduly limit the scope of my invention.

In the drawings, Fig. 1 is a longitudinal elevation view, partly in cross section and partly cut away, of a preferred specific embodiment of my invention, particularly designed and adapted for use as a fan to circulate air within an enclosure.

Fig. 2 is a view taken on line 2—2 of Fig. 1.

Fig. 3 is an elevation view, partly in cross section and partly cut away, of a preferred specific ottoman type fan embodying the new fan means of my invention.

Fig. 4 is a longitudinal view partly in cross section of a preferred specific embodiment of the new fluid moving means of my invention mounted in a fluid conduit.

Following is a discussion and description of preferred specific embodiments of the fluid moving means of my invention. In such discussion and description, reference is made to the drawings whereon the same reference numerals are used to indicate like or similar parts or structure. It is to be understood that the following discussion and description is not to unduly limit the scope of my invention.

The new fluid moving means of my invention shown in the drawings is particularly advantageously used to move air, and the fan means of Figs. 1 and 2 has a streamlined body consisting of stationary rear portion 6 and a rotatable forward end portion 8 which is preferably conoidally shaped with a smooth surface, as shown. The rear fixed portion 6 of the body houses actuation means for rotating conical end portion 8, electric motor means 10 having been found desirable. Electric motor 10 is mounted in housing 6 in any suitable manner.

Rotatable end portion 8 of the streamlined body is suitably mounted on drive shaft 12 of motor 10, such as by disks 14 affixed to cone 8 and shaft 12 in any suitable manner. It is preferred that the diameter of the fixed portion 6 of the streamlined body be substantially the same as the diameter of member 8 at point of juncture thereto, as shown in the drawings. A plurality of centrifugal blower blades 16 are mounted around the base of rotatable and conical end member 8 parallel with the longitudinal axis of the streamlined body. Such can be suitably mounted on the base end portion of member 8, as shown, or they can be separately mounted on shaft 12 between members 8 and 6 to turn with shaft 12, as desired. An outer rim 18 connects the outer ends of centrifugal blower blades 16 to support same, and blades 16 can be mounted on rim 18 in any suitable manner, such as by welding.

The streamlined body is mounted in substantially cylindrical housing 20, preferably with housing 20 extending from a point forward of rotatable end portion 8 of the body to a point overlapping the fixed rear portion 6 of the streamlined body, as shown. A plurality of stationary and longitudinally disposed curved fins 22 are mounted between housing 20 and the fixed portion 6 of the streamlined body in any suitable manner, such as by screws 24 passing through housing 20 and into fins 22, and fins 22 can be affixed to housing 6 in any suitable manner, such as by welding. Fins 22 are desirably employed to provide rectilinear flow of air exiting to the rear of the fan, and are curved in the direction shown when member 8 and the centrifugal blower blades 16 are rotated in the direction shown by the arrow on Fig. 2. If the direction of rotation of member 8 and blades 16 is the reverse of the direction shown by the arrow on Fig. 2, the curvature of fins 22 is reversed. As will be apparent to one skilled in the art, other suitable means of mounting the streamlined body in housing 20 can be employed. If desired, the curvature of fins 22 can be such as to give the non-rectilinear direction to exiting air, or the air exiting from between housing 20 and portion

6 of the housing can be allowed to move in its normal direction by eliminating fins 22 entirely. I have found it desirable to use curved fins 22, they forming with housing 20 and rear portion 6 of the body a plurality of annular air passageways, and find the mounting of the streamlined body in housing 20 to be easily accomplished by incorporating fins 22 in such mounting means, as shown. The clearance between rotatable end portion 8 and fins 22 is desirably maintained at a minimum. I find that rectilinear moving air from the fan means results in better and more air circulation within an enclosure.

The housing 20 with the streamlined body mounted therein is in turn mounted for use in any suitable manner, such as on a base 26. A connecting member 28 welded to housing 20 and base 26 has been found satisfactory to mount the fan means. Electric conduit 30 supplies power to motor means 10.

In the operation of the fan means shown in Figs. 1 and 2 of the drawings, the end member 8 having the centrifugal blower blades 16 mounted around the base thereof is rotated at a relatively high rate of speed by electric motor 10. Air moves in through the inlet in housing 20 to displace the air discharged from the housing as a result of rotating the centrifugal blower means. The free flow area between housing 20 and the portions 8 and 6 of the streamlined body preferably continually decreases gradually from inlet to outlet so that the air moving therethrough has its velocity continually increased. I have found that this enhances and maintains the pressure differential between the outside and inside of housing 20, resulting in more air being moved by my new device.

Any suitable number of centrifugal blower blades 16 can be used, and any suitable number of stationary fins 22 can be employed, keeping in mind that enough fins must be used to accomplish the purpose of directing the air, and, in addition, keeping in mind that the fins create frictional loss to reduce the amount of air moved by the fan means. I have found it desirable that surfaces over which air moves be smooth with sharp corners eliminated wherever possible so that eddy currents are eliminated. The means of my invention can conveniently be constructed of metal, plastic materials, or the like. Also, I have found it to be advantageous to mount motor 10 as shown with the exiting air moving over the housing 6 for the motor, this resulting in continual transfer of heat away from the motor, keeping it cool.

Fig. 3 depicts an ottoman type fan employing the new fluid moving means of my invention. In this instance, motor 10 is housed in fixed mushroomed portion 32 instead of the streamlined housing 6 of the embodiment of Figs. 1 and 2. Fixed portion 32 is desirably smooth faced and gently curved, as shown. The assembly is vertically disposed in any suitable manner such as by support member 34 affixed to a base 36. The ottoman fan means operates in the same manner as the fan means of Figs. 1 and 2, the primary difference being that air exiting upwardly from housing 20 is directed by member 32 in an outwardly and upwardly direction all around the fan means. I have found this ottoman type embodiment of my fan means particularly desirable to circulate the air in a room with the fan means in a central location.

In Fig. 4 is depicted the new fluid moving means of my invention incorporated in a conduit 38. Housing 40 for the streamlined body, having portions 6 and 8, also forms a portion of the conduit, being secured to portions 38 of the conduit in any suitable manner. Fins 22 can conveniently be utilized to mount the streamlined body in housing 40. Portion 8 having the centrifugal blower blades 16 is rotated at a relatively high speed, resulting in moving air in the direction of the arrows on conduit 38. As one skilled in the art can see, my new fluid moving means when used in con-

junction with a conduit results in a system taking up a minimum of space. The means of my invention as depicted in Fig. 4 readily lends itself to air circulation in a forced draft heating system, one of its chief advantages being the ease of insulating the air moving means for noise, which is important in such systems in many applications.

During operation of the means of my invention, fluid passing over the conical front element 8 of the body is forced outwardly by the centrifugal blower blades 16. 10 This movement of the fluid tends to create a low pressure zone near the surface of the conical element 8 and near the surface of the forward streamlined portion of the fixed part of the bodies 6 and 32 which preferably continue rearwardly streamlined from the rotatable conical member 8. This results in a pressure differential which in turn results in highly efficient and streamlined flow of fluid moved by the device from front to rear. The fluid moves into the device of the invention toward the low pressure zone created near the surface of element 8. 15 and rearwardly parallel to the surface of the conical member 8 and with streamline flow, not being restrained in its movement therethrough.

As will be evident to those skilled in the art, various modifications of this invention can be made, or followed, in the light of this disclosure and discussion, without departing from the spirit or scope of the disclosure or from the scope of the claims.

I claim:

1. A fan comprising, in combination: an elongated streamline body having a continuous and smooth aerodynamic surface, a forward portion of said body being rotatable and conical and a rear portion of said body being fixed, the surface of said conical forward portion of said body at its rear end being flush with the surface of said rear portion of said body at its front end, said portions of said body being closely adjacent, and said surface of said rear portion extending abruptly rearwardly from the point of juncture of said body portions; actuating means mounted in said rear portion of said streamline body connected to and adapted to rotate said conical forward portion of said body; centrifugal fan means comprising a plurality of spaced, straight and shallow blades mounted around the base of said conical forward portion of said body with the longitudinal axes of said blades parallel to the longitudinal axis of said conical forward position of said body and with the outer tip portions of said blades positioned at said point of juncture of said conical and rear body portions, an outer rim mounting and connecting the forward ends of said blades; a cylindrically-shaped housing having a forward end opening of smaller total cross sectional area than its rear end opening, said housing mounted around and enclosing said centrifugal fan means and forming an air inlet to said fan means and said housing surrounding a middle portion of said streamline body to form therewith an annular air discharge, said housing and said body defining an air flow path of gradually decreasing cross sectional area from front to rear of said rotatable forward portion of said body; a plurality of stationary, longitudinally disposed and curved fins mounted between the rear portion of said housing and said middle portion of said streamline body, said fins defining a plurality of air passageways and adapted to direct rearwardly moving air in a rectilinear direction; and means to mount said streamline body and cylindrically-shaped housing.

2. A fan comprising, in combination, streamlined body having a continuous and smooth aerodynamic surface, one end portion being rotatable and conoidally-shaped, the remainder of said body being fixed and housing actuating means for rotating said rotatable end portion, the surface of said conoidally-shaped portion at its inner end portion being substantially flush with the surface of said remainder of said body at its inner end portion,

said portions of said body being closely adjacent, and said surface of said remainder of said body extending substantially abruptly and longitudinally away from the point of juncture of said body portions, a plurality of spaced, straight and shallow centrifugal blower blades mounted around the base of said conoidally-shaped end portion with the longitudinal axis of said blades parallel to the longitudinal axis of said streamlined body and with the outer tip portions of said blades closely positioned at said point of juncture of said conoidally-shaped body portion and remainder of said body, a cylindrically-shaped housing having an inlet of less total cross sectional area than its outlet mounted around said rotatable end portion and forming an air inlet forward of same, said housing forming with said streamlined body an annular air outlet rearward of said rotatable end portion and said housing and said body defining an air flow path of decreasing cross sectional area from front to rear of said rotatable end portion, and fin means adapted to direct air moving from said rotatable end portion in a rectilinear direction.

3. A fluid moving device, comprising, in combination, a streamlined body having a continuous and smooth aerodynamic surface, said body having a conoidal and 25 rotatable end portion and a smooth and gently curved fixed end portion, the surface of said conoidal end portion at its inner end portion being substantially flush with the surface of said fixed end portion at its inner end portion, said portions of said body being closely adjacent, 30 and said surface of said fixed end portion extending substantially abruptly and longitudinally away from the point of juncture of said body portions, a plurality of spaced, straight and shallow centrifugal blower blades mounted around the base of said conoidal end portion, 35 with the longitudinal axes of said blades parallel to the longitudinal axis of said body and with the outer tip portions of said blades closely positioned at said point of juncture of said conoidal body portion and fixed body portion, and a housing around said rotatable end portion and a portion of said fixed portion of said body, 40 said housing having less total cross sectional area forward of said rotatable end portion than at a point immediately to the rear of same.

4. An ottoman fan comprising, in combination: a body having a continuous and smooth surface, a lower portion of said body being rotatable and conical and an upper portion of said body being fixed and mushroomed the surface of said conical lower portion of said body at its upper end being flush with the surface of said upper portion of said body at its lower end, said portions of said body being closely adjacent, and said surface of said upper portion extending abruptly upwardly from the point of juncture of said body portions; actuating means mounted in said upper portion of said body connected 45 to and adapted to rotate said conical lower portion of said body; centrifugal fan means comprising a plurality of spaced, straight and shallow blades mounted around the base of said conical lower portion of said body with the longitudinal axes of said blades parallel to the longitudinal axis of said conical lower portion of said body, and with the outer tip portions of said blades positioned at said point of juncture of said conical and rear body portions, an outer rim mounting and connecting the forward ends of said blades; a cylindrically-shaped housing 50 having a lower end opening of smaller total cross sectional area than its upper end opening, said housing mounted around and enclosing said centrifugal fan means and forming an air inlet to said fan means and said housing surrounding the lower portion of said mushroomed upper portion of said body to form therewith an annular air discharge, said housing and said body defining an air flow path of gradually decreasing cross sectional area from front to rear of said rotatable lower portion of said body; a plurality of stationary, longitudinally disposed 55 and curved fins mounted between the upper portion of

said housing and the lower portion of said upper portion of said body, said fins defining a plurality of air passageways and adapted to straighten the flow of spiraling air from said centrifugal fan means; and support means to mount said body and said cylindrically-shaped housing with their longitudinal axis vertical.

5. A fan comprising, in combination, a body, one end portion being rotatable and conoidally-shaped, the remainder of said body being fixed and mushroomed and housing actuating means for rotating said rotatable end portion, the surface of said conoidally-shaped portion of said body at its inner end portion being substantially flush with the surface of said remainder of said body at its inner end portion, said portions of said body being closely adjacent, and said surface of said remainder of said body extending substantially abruptly and longitudinally away from the point of juncture of said body portions, a plurality of spaced, straight and shallow centrifugal blower blades mounted around the base of said conoidally-shaped end portion with the longitudinal axes of said blades parallel to the longitudinal axis of said body and with the outer tip portions of said blades closely positioned at said point of juncture of said conoidally-shaped body portion and remainder of said body, a cylindrically-shaped housing having an inlet of less total cross sectional area than its outlet mounted around said rotatable end portion and forming an air inlet forward of same, said housing forming with said body an annular air outlet rearward of said rotatable end portion and said housing and said body defining an air flow path of decreasing cross sectional area from front to rear of said rotatable end portion, and fin means adapted to straighten the flow of spiraling air from said rotatable end portion.

6. Fluid moving means, comprising, in combination, an elongated streamline body having a continuous and smooth aerodynamic surface, a forward portion of said body being rotatable and conical and a rear portion of said body being fixed, the surface of said conical forward portion of said body at its rear end being flush with the surface of said rear portion of said body at its front end, said portions of said body being closely adjacent, and the said surface of said rear portion extending abruptly rearwardly from the point of juncture of said body portions; actuating means mounted in said rear portion of said streamline body connected to and adapted to rotate said conical portion of said body; centrifugal fan means comprising a plurality of spaced, straight and shallow blades mounted around the base of said conical forward portion of said body with the longitudinal axes of said blades parallel to the longitudinal axis of said conical forward portion of said body and with the outer tip portions of said blades positioned at the point of juncture of said conical and rear body portions; an outer rim mounted and connecting the outer ends of said blades; a conduit surrounding said streamline body from a point

in front of said rotatable forward portion of said body to a point to the rear of said fixed rear portion of said body, the total cross sectional area of said conduit in front of said rotatable forward portion being less than the total cross sectional area of said conduit at a point immediately to the rear of said rotatable forward portion of said body and said conduit and said body defining a fluid flow path of gradually decreasing cross sectional area from front to rear of said rotatable forward portion of said body; and a plurality of stationary, longitudinally disposed and curved fins mounted between said conduit and said fixed portion of said streamline body, said fins defining a plurality of fluid passageways and adapted to straighten the flow of spiraling fluid moving rearwardly from said centrifugal fan means.

7. A fan comprising, in combination, a body, said body having a conoidal and rotatable end portion and a mushroomed smooth and gently curved fixed end portion, the surface of said conoidal end portion at its inner end portion being substantially flush with the surface of said fixed end portion at its inner end portion, said portions of said body being closely adjacent, and said surface of said fixed end portion extending substantially abruptly and longitudinally away from the point of juncture of said body portions, centrifugal blower means comprising a plurality of spaced, straight and shallow blades mounted around the base of said conoidal end portion with the axes of said blades parallel to the longitudinal axis of said body and with the outer tip portions of said blades closely positioned at said point of juncture of said conoidal body portion and fixed body portion, and a housing around said rotatable end portion and a portion of said fixed portion of said body, said housing having less total cross sectional area forward of said rotatable end portion than at point immediately to the rear of same.
